UNITED STATES PATENT OFFICE.

CHARLES S. PINKHAM, OF PHILADELPHIA, PENNSYLVANIA, ASSIGNOR OF
ONE-HALF TO JAMES J. SEAL, OF SAME PLACE.

AUTOMATIC ELECTRICAL CUT-OUT.

SPECIFICATION forming part of Letters Patent No. 294,404, dated March 4, 1884.

Application filed June 14, 1883. (No model.)

To all whom it may concern:

Be it known that I, CHARLES S. PINKHAM, a citizen of the United States, and a resident of Philadelphia, Pennsylvania, have invented
5 an Improved Automatic Electrical Cut-Out, of which the following is a specification.

The main object of my invention is to so provide an open-circuit line with an automatic cut-out or switch as to prevent the battery from running down when the line becomes accidentally grounded, and to restore the normal arrangement when the "ground" is removed.

15 A further object of my invention is to construct an improved electro-magnetic switch for carrying the above feature of my invention into effect.

These objects I attain as more fully described hereinafter.

20 In the accompanying drawings, Figure 1 is a diagram illustrating my invention; Fig. 2, a front view of my electro-magnetic switch with the cover removed; Fig. 3, a side view with the cover in section; Fig. 4, a perspective view of a portion of the instrument; Fig. 25 5, a diagram of the commutator-face, and Fig. 6 a front view of the instrument drawn to a reduced scale.

Referring to the diagram Fig. 1, L is the 30 line-wire; D, an instrument on the line to be operated, (in this instance an electric gas-lighter is shown,) having a ground-connection, G', through a conductor, d. X is the electro-magnetic switch having two contacts, 2, 3, leading to a ground, G, through conductors b and b', one having a Leclanché or other open-circuit battery, B, and the other a "blue-stone" or other constant battery, B', in circuit. The switch consists of a commutator, C, having the 35 three contacts 1, 2, 3 bearing on it, the second and third connecting with the batteries B and B', while No. 1 is connected with the coils of an electro-magnet, E, going to the line in this instance. This electro-magnet acts on an armature, A, which is so connected to the commutator C that when the armature is attracted by the electro-magnet against the action of a spring or weight, a, or other retractor, the contact No. 2, normally in electrical communication with No. 1, will be brought into con-

tact with an insulated space and cut-out of circuit, while No. 3, normally on an insulated space on the commutator, will be brought into electrical communication with No. 1. Under normal conditions the commutator is in the 55 position shown in the drawings, with the Leclanché or similar open-circuit battery, B, to the line and the blue-stone or constant battery B' out; but should the line be grounded, the closure of the circuit will cause the attraction 60 of the armature A by the electro-magnet E, whereby the commutator C will be so turned or otherwise moved as to bring the contact 2 onto an insulated portion of its face, while No. 3 is brought onto a metallic portion thereof, and into 65 electrical connection with No. 1 and the line. Thus the open-circuit battery B is cut out and the constant battery B' is thrown into the closed circuit, and the latter will so remain as long as the line is grounded; but when the ground 70 is removed the armature will be relieved from the attraction of the electro-magnet and withdrawn by the retractor, so as to move the commutator C back to the position shown in Fig. 1, with the battery B cut out and the battery 75 B reinstated, ready for use for operating the instrument D. By this means the inconstant battery B will be saved from polarization by the accidental grounding of the line, and will be kept off the line so long as the ground remains, owing to the employment of the battery B' in the circuit, while the battery B is automatically reinstated when the line is cleared.

It will be understood that the operation of the instrument or instruments D (electric gas-lighter or signaling-instrument, for instance) will cause the closing of the circuit and attraction of the armature A by the electro-magnet to operate the commutator; but this is immaterial, as the battery B is always automatically reinstated as soon as the line-circuit is opened, and under ordinary circumstances the closure of the circuit to operate the instrument D is so momentary as to merely cause a fluctuation of the armature A without moving the commutator far enough to change the circuits, and for this purpose I combine with the commutator a device for retarding and steadyng its movement, as hereinafter described.

The connections of the automatic cut-out to 100

the line and to the ground may be reversed, if desired, without changing the operation or result. Thus the united ends of the conductors $b b'$, with their respective batteries $B B'$, 5 may be connected to the line, while the contact 1 through the coils E is connected to the ground.

I will now proceed to describe the detailed construction of my electro-magnetic switch I 10 use in carrying out the above-described feature of my invention.

Referring to Figs. 2 and 3, M is a base-board, to which is secured the frame M' , carrying the electro-magnetic coils E , one terminal of which 15 is connected, as indicated by dotted lines, to the binding-post 4, while the other terminal is connected to the spring-contact 1, carried by the insulation-post F , Figs. 2 and 4. To the same insulation-post, F , are secured the other 20 two spring-contacts, 2 and 3, electrically connected to binding-posts 5 and 6, respectively.

The armature A , mounted on pivot-pins on the frame M' and acted on by the electro-magnet E , is connected by a link, a' , to an arm on 25 the commutator C , which in this case is in the form of a cylinder having a spindle mounted in bearings in the frame M' . The spring-contacts 1, 2, and 3 bear on the periphery of this cylindrical commutator, which is provided 30 with the insulation-spaces (shown in Fig. 4 and the diagram Fig. 5) to come into contact with either the spring 2 or the spring 3, according to the position assumed by the commutator. To retract the armature when the circuit 35 through the electro-magnet is opened, I prefer to use a weighted arm, a , which is secured to the axis of the cylinder C , so that when the instrument is placed in the vertical position (shown in Figs. 2 and 3) this weighted arm 40 will tend to keep the armature in the position shown in said Fig. 2, away from the electro-magnet E .

A spring may be used in place of the weight; but I prefer the weight, as it is steadier in its 45 action, and as the armature approaches nearer the poles of the electro-magnet the weighted arm rises and offers increased resistance, owing to the increasing leverage.

Instead of making the contacts 1 2 3 of the 50 switch fixed and the commutator movable by the action of the armature, the commutator may be fixed and the spring-contacts be movable over the face of the fixed commutator by the action of the armature A .

To steady and retard the action of the switch, I combine therewith a fly-wheel or fan, P , on a spindle, p , in bearings in the frame M' , and having a pinion, p' , gearing into a quadrantal rack, Q , secured to the spindle of the commutator. It will be understood that other arrangements of gearing may be used to transmit the motion of the armature to the fan P .

The operation of the device will be readily understood from the foregoing description.

I combine with the switch an indicator to 65 show when there is any interference with the

line and when the line is clear. This indicator I have shown as consisting of a disk, R , mounted on a pivot on the inside of the lid N , and weighted at one edge, so as to tend to stay 70 in one position with the word "Clear," or a certain color or signal showing through an opening, n , in the cover. On the opposite side of the disk is a pin, r , Fig. 3, in the path of an arm, r' , on the spindle of the commutator, 75 so that when the armature is attracted by the electro-magnet on the grounding of the line, and turns the commutator C to switch the open-circuit battery out and the constant battery into circuit, the arm r' will strike the pin r and 80 turn the disk R to show the word "Ground," or a different color or signal from what is visible when the line is in normal working order. As soon as the ground is removed from the line, the weight q draws back the commutator, 85 armature, and arm r' , and allows the weighted disk to return to its normal position to indicate a clear circuit.

By the term "open-circuit battery" as used in the foregoing description I wish to be understood as referring to the Leclanché or other battery adapted for use only on open circuits, and which rapidly polarizes when used on a closed circuit, while by the term "constant battery" I mean a battery—such as the sulphate-of-copper battery—which can be used on a closed circuit for an indefinite length of time without running down. 95

In order to keep the gravity-battery always on a closed circuit, I combine therewith a resistance-coil, T , Fig. 1, which forms a short circuit for the battery when the latter is off the line. 100

I claim as my invention—

1. The combination of an open-circuit line 105 and an open-circuit battery with a constant battery and an automatic switch, substantially as described, whereby on the continued grounding or closure of the circuit the open-circuit battery will be cut out and the constant battery thrown into circuit, substantially as set forth.

2. The combination of an open-circuit line and its working-battery with a constant battery, an electro-magnet in the circuit, and a 115 switch controlled by the electro-magnet to throw the working-battery out of and the constant battery into circuit on the continued closure of the circuit, substantially as described. 120

3. The combination of an open-circuit line and its working-battery with a constant battery, an electro-magnet in the line-circuit, its armature, a switch controlled by the armature, and a retractor for the armature, whereby the open-circuit battery is thrown out and the constant battery is thrown into circuit on the continued closure of the circuit, and the normal arrangement restored automatically on the re-opening of the circuit. 125

4. The combination of an open-circuit line and its working-battery with a constant bat- 130

- tery, an electro-magnet in the circuit, its armature, a commutator operated by the movement of the armature, and contacts for the commutator, substantially as described, where-
5 by on the continued closure of the line-circuit the working-battery will be thrown out and the constant battery thrown into circuit.
5. The combination of an electro-magnet, armature, and a switch operated by the armature and a retractor with a fan geared to the switch to retard the action of the armature.
10. The combination of the electro-magnet, armature, commutator operated thereby, and contacts with a retractor and a fan geared to the commutator, substantially as set forth.
15. The combination of an electro-magnet and armature, with a retractor, contacts, a commutator-cylinder mounted in bearings and
- operated by the said armature, and carrying a quadrantal rack, and a fan having a pinion 20 gearing into said rack, all substantially as described.
8. The combination of an open-circuit line and open-circuit battery with a constant battery, an automatic switch to cut out the open- 25 circuit battery and put the constant battery into circuit, and a signal operated by the switch, substantially as set forth.
- In testimony whereof I have signed my name to this specification in the presence of two 30 subscribing witnesses.
